UNITED STATES PATENT OFFICE.

GEORGE ZISTER, OF CHICAGO, ILLINOIS.

SHEET-PILEING.

932,231.

Specification of Letters Patent. Patented Aug. 24, 1909.

Application filed September 8, 1906, Serial No. 353,784. Renewed June 4, 1909. Serial No. 500,199.

To all whom it may concern:

Be it known that I, GEORGE ZISTER, citizen of the United States, residing at Chicago, in the county of Cook and State of Illinois, have invented new and useful Improvements in Sheet-Piling, of which the following is a specification.

This invention relates to improvements in metal sheet piling for use in the construction of sea-walls, docks, levees, and all other purposes for which this class of piling can be utilized.

The general object of my invention is to provide sheet piling sections or members whereof the interlocking features necessary for holding the sections together when assembled, are made integral with the sections, which are identical with one another in sectional form. Thus the employment of separate interlocking devices mechanically secured to the members, is dispensed with.

The special object of my invention is to provide a sheet piling structure the members of which are positively and rigidly interlocked, against relative or angular movement of any kind, after assemblage.

To this end my invention consists in providing individual piling sections having the conformation hereinafter described.

Referring to the drawings, Figure 1 is a plan or end view of a piling section before the respective edges are turned inward to form the required interlock. Fig. 2 is a plan or end view showing a number of completed sections interlocked. Fig. 3 is an elevation of the same. Fig. 4 is a plan or end view of a modified form; and Fig. 5 is an elevation of the same.

The preliminary step in the manufacture of my improved piling is to roll the web sections or members A substantially flat with the respective edges and adjacent part upset or thickened as shown at a. The thickened edge portions are formed on what may be termed the inner or interlocking sides of the sections, leaving the opposite sides on a straight line with the web part as shown in Fig. 1. The thickened edges are rounded as at b and grow thinner inward and vanish in the body of the web along the beveled line 6. In the next and final step the thickened edges are bent inward in the direction of each other, bringing the interturned part into a plane approximately parallel to the body of the web and forming interlocking hook-edges 7, as shown in Fig. 2. In this position the

inturned edges stand away from the body of the web or plate and provide dovetailed grooves 8 extended the full length of each section. The contour of the inturned edges 60 correspond to the shape of the grooves 8 and form a dovetailed interlock when the sections are assembled, in a wall structure, as shown in Fig. 2.

The sections are all exact duplicates of 65 each other but for the purpose of description the reference letter B will be used on the middle section shown in Fig. 2. When the sections are assembled in practical use they are telescoped together endwise and arranged alternately, that is, the backs of the sections A and B are on opposite sides in the wall which order of arrangement is continuous in a structure.

It will be noted that the sections, though, 75 assembled endwise are interlocked edgewise and in the operation of driving cannot be displaced, as the thick rounded edge cannot be withdrawn through the narrow contracted part 9 of the grooves 8. 80

Figs. 4 and 5 show a modified form in that the inturned locking hook edges stand at right angles with reference to the body of the piling sections. The same reference characters are employed in the modifications. 85

The proportions of the interlocking edges will be such that the sections will go together loosely so that they may be assembled with facility and easily drawn out when used in temporary structures. 90

Having thus described my invention, what I claim is—

1. In sheet-piling, a section consisting of a body or web having its edges turned inward to form an interlock, said turned in edges gradually growing thicker in an outward direction. 95

2. A sheet-piling section consisting of a metal plate or body having its respective 100 edges turned inward to form an interlock with a duplicate joining section, said turned in edges gradually growing thinner from the extreme edge inward and vanishing in the plate or body part. 105

3. A sheet-piling section, consisting of a flat plate or body having interlocking hook-edges formed thereon, said hook edges being thicker than the plate-part and gradually growing thinner from the extreme edge inward. 110

4. A sheet piling structure composed of a

series of sections, each having hooked edges of dovetail section, the grooves within said hooked edges being of dovetail form, and the dovetail edges fitting within the grooves formed by the hooked edges of the joining pile sections.

5. A sheet-piling section, consisting of a web-part having its respective edges turned inward parallel with the face of the web-part and separated by an intervening space, said space corresponding in outline to the contour of said inturned edges and forming an interlock permitting of endwise separation only.

10 6. A sheet-piling section, consisting of a web-part having its edges turned inward on a line with said web-part, said inturned edges gradually thickening outward to a rounded contour and separated from the

web-part by a space generally enlarging inward and adapted to receive the corresponding edge of a joining section.

7. In sheet-piling, a piling section having its respective edges turned inward parallel to the web-part and leaving an intervening space, said inturned edges gradually thickening outward forming a rounded dovetail, said intervening space having an outline corresponding to the rounded dovetail edge in reverse, and a duplicate joining pile section loosely interlocking therewith in forming a continuous wall structure.

In testimony whereof I affix my signature, in presence of two subscribing witnesses.

GEORGE ZISTER.
